UNITED STATES PATENT OFFICE.

WILLIAM J. YOUNG, OF LYNN, MASSACHUSETTS.

COUNTER-SKIVING MACHINE.

SPECIFICATION forming part of Letters Patent No. 620,010, dated February 21, 1899.

Application filed January 26, 1898. Serial No. 668,071. (No model.)

To all whom it may concern:

Be it known that I, WILLIAM J. YOUNG, a citizen of the United States, residing at Lynn, in the county of Essex and State of Massachusetts, have invented certain new and useful Improvements in Counter-Skiving Machines; and I do hereby declare the following to be a full, clear, and exact description of the invention, such as will enable others skilled in the art to which it appertains to make and use the same.

The present invention relates to skiving-machines, and more particularly to a skiving-machine for skiving off or beveling boot and shoe counters.

The object of the present invention is to produce a counter-skiving machine which shall be simple in construction and quick and efficient in action and to so arrange the skiving mechanism that there shall be no danger of cutting or injuring the hands of the operator.

To the above end the present invention consists of the devices and combinations of devices which will be hereinafter described and claimed.

The present invention is illustrated in the accompanying drawings, in which—

Figure 1 illustrates a front elevation of a machine embodying the same. Fig. 2 illustrates a side elevation of the machine looking from the left of Fig. 1. Fig. 3 illustrates a top plan view of the front portion of the machine. Fig. 4 illustrates a top plan view of the rear portion of the machine, parts being broken out to show underlying parts. Fig. 5 is a fragmentary view of a portion of the machine, parts being shown in front elevation and other parts being in section.

Similar letters of reference designate corresponding parts throughout the several views of the drawings.

Before proceeding to a detailed description of the present invention it may be stated that the machine, generally speaking, has a work-supporting table and a knife-block carrier, which have relative movements toward and from each other to place the material on the work-support in position to be acted upon by the skiving-knife, and also said knife-carrier and work-support have relative movements longitudinally with relation to their length

in order to skive and bevel off the projecting edge of the material, and while in the machine of the drawings, which will be herein-after described in detail, the relative movements of the work-support and knife-carrier toward and from each other are produced by a movement of the work-support toward and from the knife-block carrier and the relative longitudinal movements of the work-support and knife-block carrier are produced by a longitudinal reciprocation of the knife-block carrier with relation to the work-support, the present invention is not limited thereto, as the relative movements described may be produced by moving the knife-carrier toward the work-support and the work-support be moved longitudinally with relation to the knife-carrier.

In the drawings, A represents a suitable supporting-frame, which may be of any convenient form and arrangement, to support the working parts of the machine, said frame in the machine of the drawings comprising a base ⁷⁵ a, upon the upper surface of which are vertically-projecting standards a' , a'' , and a''' .

In the standards a' and a'' are suitable bearings a^3 and a^4 , in which is mounted to rotate a shaft B, said shaft being provided with a ⁸⁰ driving-pulley b, arranged to be driven by a belt from any suitable source of power, the pulley b being loose on said shaft and having a beveled inner face b' , which is arranged to engage the beveled face b^2 of a clutch-pulley b^3 , ⁸⁵ fixed to rotate with said shaft, the pulley b being arranged to have a slight movement along the shaft B, whereby the beveled faces b' and b^2 of the pulleys b and b^3 are brought into contact and motion imparted to the shaft ⁹⁰ B from the constantly-running pulley b, and when the beveled faces are disengaged the shaft B will be at rest. Mounted in suitable bearings a^5 , formed in a standard a'' upon the upper surface of the base a and extending ⁹⁵ parallel to the shaft B, is a shaft B', said shaft B' being driven from the shaft B by means of a pinion b^4 , fixedly secured to shaft B and gearing with a gear b^5 , fixedly secured to the shaft B'.

The front of the standard a' is formed with projecting portions or ribs a^7 and a^8 , which are cut out or rabbeted, as at a^9 , said rabbets a^9 in connection with a plate a^{10} , secured to

the projecting portion a^7 by bolts a^{11} , and a plate a^{12} , secured to the projecting portion a^8 , forming a guideway for the reciprocating knife-block carriage C, which, as will be hereinafter described, is arranged to have a reciprocation along said guideway.

The carriage C comprises a rectangular plate, the upper and lower edges of which fit into the guideways in the front of the stand 10 and a' , and in the machine of the drawings, said carriage is arranged to be reciprocated along said guideways by a link c , which is pivoted at c' to the back of said carriage, and which, at its opposite end, is pivoted at c^2 to 15 a crank-pin c^3 , carried by a disk c^4 , affixed to the shaft B' .

The above arrangement is such that a rotation of the main shaft B will rotate the shaft B' , and, through the link c , impart the reciprocating movement to the carriage C.

Upon the front face of the carriage C is mounted a knife-block D, said knife-block having secured to its under face suitable skiving-knives d , and in order that said skiving-knives d may have their cutting edges presented at the proper cutting-angle to the stock to be skived, which will be upon the work-support, said knife-block in the machine of the drawings is fulcrumed to oscillate 25 upon the carriage C to lower one knife and raise the other automatically, according to the direction of travel of said carriage, and in the present invention the oscillation of the knife-block is arranged to be automatically 30 performed by the following mechanism.

The knife-block D comprises a plate or casting which has a vertical or upright portion d^1 and a horizontal portion d^2 , the vertical portion d^1 being fulcrumed at d^3 to the carriage C and the horizontal portion carrying the skiving-knives d , said knives d being secured in position on the under face of the horizontal portion d^2 of the knife-block D, with their cutting edges d^4 arranged outwardly or at opposite ends of the knife-block, 45 as clearly shown in Fig. 5 of the drawings.

In the machine of the drawings when the carriage C is moving in the direction of the arrow shown in Fig. 5 of the drawings the knife-block D will be in the position shown in said figure, with the right-hand end depressed to bring the skiving-knife at that end in a proper angular position to engage and skive the stock upon the work-support, and just as it completes its stroke in the direction indicated the knife-block will be automatically oscillated and the opposite end depressed to bring the knife on the left in cutting position for action on the return stroke of the carriage C. 50 Suitable latches or locking devices are provided to hold the knife-block in either of its positions during the action of the cutters, and these latches are arranged to be automatically released as the carriage C reaches the limit of its stroke in either direction.

The automatic oscillating and locking mechanism of the knife-block D in the ma-

chine of the drawings comprises suitable plungers or rods d^5 , which are mounted to slide in suitable bearings d^6 , carried by the plate a^{10} , 70 said rods having heads or enlargements d^7 upon their outer ends in order to limit their movement in one direction or toward each other. Said rods d^5 are surrounded by suitable coiled springs d^8 , which bear at one end 75 against the inner surface of the end bearings d^6 and at the other end against a shoulder d^9 , formed upon said rods, whereby the rods will be normally pressed toward each other or toward the medial line of the machine. 80

Upon the upper edge of the knife-block D is a projection $d^{\times}$, which is arranged to come into contact with the inner ends of the rods d^5 upon the reciprocation of the carriage C and move said rods in their bearings against 85 the tension of the springs, it being understood that the projection $d^{\times}$ will engage the rod toward which it may be moving. After the projection $d^{\times}$ has engaged the end of the rod d^5 toward which it may be moving the further 90 movement of the carriage C and knife-block D will cause the rod to move backwardly in its bearings and the spring to be compressed, and just before the carriage C reaches the limit of its stroke the rod d^5 then in contact 95 with the projection $d^{\times}$ will be exerting considerable pressure upon said projection, such pressure being sufficient upon the unlocking or releasing of the knife-block D to swing said knife-block upon its fulcrum d^3 to depress 100 its opposite end, in which position it will be locked for the return movement of the carriage C.

As shown in the drawings, the machine comprises spring-bolts which are arranged to automatically lock the knife-block as it is oscillated, and suitable means are provided for releasing the bolts as the carriage C reaches the limit of its stroke in either direction in order to permit the knife-block D to be oscillated and tilted for the return stroke. 105

The locking and releasing mechanism of the machine of the drawings comprises bolts E, which are arranged to have a sliding motion in suitable bearings e , formed in the 115 knife-block D, suitable springs e' in said bearings acting upon the inner ends of said bolts to normally press them outwardly, and the outer ends of said bolts E are arranged to engage the curved faces e^2 of suitable blocks 120 or keepers e^3 , carried by plates e^4 , secured by bolts e^5 to the ends of the carriage C, said keepers e^3 being provided below the curved faces e^2 with notches e^6 , with which the bolts E are arranged to engage as the ends of the 125 knife-block D are depressed. The keepers e^3 are slotted, as shown at e^7 , and projecting into and through these slots are pins or projections e^8 , formed on the ends of the bolts E, said pins e^8 being arranged to be engaged by 130 suitable stops or arms e^9 , formed on upwardly-projecting arms e^{10} , carried by the plate a^{12} , said stops e^9 acting to force the pins e^8 inwardly against the tension of the springs e'

to thus remove the bolts E from the notches e⁶ to release the knife-block and permit the plunger d⁵ then in contact with the projection d⁴ to swing the knife-block D on its fulcrum, raising one end and depressing the other end for the return movement of the carriage C. It will thus be seen that the knives d are alternately raised and lowered to be brought into operative engagement with the work, one knife cutting as the carriage C moves in one direction and the other knife cutting as the carriage moves in the opposite direction.

In this connection I desire to state that in so far as I am at present advised of the state of the art it has never been proposed to provide a reciprocating knife-block or carrier with two cutters and means to automatically move said cutters into and out of operation upon the reciprocation of said knife-block to alternately position said cutters to make their cuts from the medial portion of the material toward the ends thereof, and while in the illustrated embodiment of my invention I attain this result by an oscillating knife-block, I do not consider my invention as limited thereto, but intend to claim the same in the broadest legal sense.

As before stated, the knives are secured to the under side of the horizontal portion d² of the knife-block with their cutting edges d⁴ arranged at opposite ends, and in advance of the cutting edges d⁴ are arranged suitable pressers to engage the counter or other material to be skived in advance of the cutting edges to press said counter against the work-support and moving along with said cutters smooth out the material for the action of said cutters, and in the case of skiving counters where said counter is laid upon a die-faced cutting-bed into which said counter is pressed and the portion of the counter projecting above the recess skived off the pressers act to force said counter into the recess of the bed as the knife advances to skive off the projecting portion of the counter.

The pressers in the machine of the drawings are shown at F and comprise a number of small bell-crank levers f, which are fulcrumed upon rods f², said rods f² being supported by the vertical portion d' and by a plate p^{*}, secured by bolts p'* to the portion d² of the knife-block D. The lower ends of the bell-crank levers f are rounded, as shown, to engage the work, and the upper ends of said levers rest against a cushion f⁵, said cushion comprising a block of rubber or other suitable material arranged to permit the independent yielding of the levers f, whereby they will be adapted to conform to the inequalities of the material being skived. The cushions f⁵ are arranged in recesses f⁶, formed in the brackets f³, secured to the knife-block D by bolts f⁴, and suitable adjusting-screws f⁷ are tapped into apertures in the brackets arranged to bear upon the rear faces of said

cushions for the purpose of adjusting the pressure of the same.

In order to adjust the position of the lower ends of the levers f with relation to the cutting edges of the knives d, bars f⁸ are adjustably held in contact with the inner faces of the upper ends of said levers, said bars f⁸ being acted upon by suitable adjusting-screws f⁹, whereby the bars f⁸ may be moved back and forth with relation to the cushions f⁵ to raise and lower the lower end of the levers f.

The knives d in the present invention are held in position by an undercut rib g, formed along the back of the under side of the horizontal portion d² of the knife-block and by plates g', having undercut ribs g², which are fastened to the front of the portion d² of the knife-block by the bolts p'*¹, the ribs g and g² engaging the side edges of the knives d and holding them securely in position.

The work-support H in the machine of the drawings comprises a substantially rectangular table h, which is arranged for a vertical movement toward and from the knives d, said table having a removable die-plate h' upon its upper surface, in which is formed a recess or die h², into which the counter to be skived is depressed, leaving portions of the edge projecting to be cut off by the skiving knives d, said die-plate h' being cut away at its central portion, as shown at h³, for a purpose to be hereinafter described.

The table H is provided with a depending shank or stem h⁴, which is arranged to have a vertical reciprocation to elevate and lower the table H in a guide h⁵, formed in a projection h⁶ on the front of the base a, and said shank or stem h⁴ is retained in said guide h⁵ by a plate h⁷, secured to the front of said projection by screws h⁸.

The table H is raised by a cam h⁹, which engages a cam-roll h¹⁰, mounted upon the rear face of the shank h⁴, said cam-roll being preferably mounted in an eccentric stud and which has a threaded portion around its periphery which is engaged by a screw h¹¹, whereby said stud may be turned to adjust the vertical throw of the table or work-support H. The cam h⁹ is carried by a rock-shaft K, which is mounted in suitable bearings in the base a and in a bearing k in a short standard k', said shaft carrying a belt-pulley k², which is connected by a belt k³ with a pulley k⁴ on the shaft B.

The shaft K is a rock-shaft arranged to be turned sufficiently to cause the cam to raise the table or work-support H and to be turned in the opposite direction to reverse the cam and permit the shank and table H to fall by gravity by means of a spring k⁵, which is connected at its upper end to a fixed bar k⁶ and at its lower end to a lug k⁷, carried by a collar k⁸, fixedly secured to the shaft K. The clamp for clamping the counter in position upon the die-plate h' of the work-support H is arranged to automatically clamp the

counter upon the elevation of the work-support and to release said counter upon the depression of said work-support.

The clamp in the machine of the drawings 5 comprises a yoke M, arranged, as shown, to cross the bed or work-support H, the legs m of the yoke passing through bearings m' on a fixed portion of the machine and surrounded below said bearings with coiled springs m², 10 said springs m² being confined between the lower ends of said bearings and suitable heads m³, formed on the legs m, the cross-bar m⁴ of the yoke M being arranged to draw the central portion of the counter down into the 15 cut-out portion h³ of the die-plate h' and against a stationary clamping-plate m⁵, secured in a groove m⁶ in the bed or table H, the upper surface of said clamping-plate and the under surface of the cross-bar m⁴ being 20 roughened or serrated in order to frictionally grip the counter. The above arrangement is such that as the table or work-support H rises the counter will come in contact with the cross-bar m⁴ of the clamp M just before the table has reached the limit of its upward movement, and in the further upward movement of said work-support the clamp will draw the central portion of the counter down into the recess h³ in contact with the 25 plate m⁵, the springs m² yielding in the further upward movement of the work-support, thus yieldingly but firmly clamping the counter in position to be acted upon by the knives d, and upon the lowering of the table 30 or work-support H the counter will be automatically released, as will be clearly apparent from an inspection of the drawings.

In the present invention the mechanism which actuates the knife-carriage and the 40 mechanism which acts to raise the work-support are controlled by suitable clutches and connecting mechanism, so arranged that a downward depression of a foot-treadle (not shown) will cause the rock-shaft K to be 45 turned to raise the work-support H and hold said support raised, with the material to be skived clamped thereon in position to be acted upon by the skiving-knives, and to thereafter rotate shaft B to impart motion to shaft B' 50 to cause a reciprocation of the knife-carriage C and to automatically stop after one excursion of the knife-carriage, leaving said carriage in its starting position and the work-support lowered. In the machine of the drawings 55 this mechanism is so arranged that motion being imparted to the shaft K to raise the work-support said shaft through connecting mechanism acts to connect the constantly-running pulley b with shaft B, to thus 60 impart a rotation to such shaft and shaft B' to reciprocate the knife-carriage C.

To secure the above-suggested result in the machine of the drawings, the pulley k² is loosely mounted upon the shaft K and free 65 to turn thereon, and said pulley k² is constantly driven by the belt k³ from pulley k⁴, which is connected to and driven by the pul-

ley b. The pulley k² is arranged to be locked to the shaft K by a suitable clutch mechanism comprising a friction-surface carried by 70 an element fixed on said shaft and a friction-surface carried by a part movable along the shaft K toward and from the fixed element.

As shown, the fixed friction-surface may be formed on a pulley p, which is secured to 75 the shaft K, and the movable friction-surface may be formed on the pulley k², said pulley being moved toward and away from the pulley p by a fork p', which takes into a groove p², carried by a hub p³, formed on the pulley 80 k². The fork p' is formed on one arm of a bell-crank lever p⁴, which is fulcrumed at p⁵ to the frame a, and the opposite end of said bell-crank lever is connected, by means of a link or rod p⁶, to a foot-treadle. (Not shown.) 85

Upon shaft K is fixed a collar p⁷, from one face of which projects a pin p⁸, which is arranged to engage the hooked end p⁹ of a rod p¹⁰ when the shaft K is rocked, which rod controls the clutch mechanism which connects 90 the pulley b and shaft B, as will now be described.

The pulley b is moved toward and from the pulley b³ by a lever t, which is fulcrumed at t' to the standard a² and which at the upper end is provided with a collar t², which engages a groove t³, formed in a hub t⁴ of the pulley k⁴, which is fixed to the pulley b, and said pulleys are moved in one direction to bring the clutch-faces b' and b² into frictional 95 engagement by means of a spring t⁵, which at one end is connected to the lower end of the lever t and at the other end to the standard a², preferably by means of an adjusting-bolt t⁶. The lever t is moved against the tension of 100 spring t⁵ to move pulley b away from pulley b³, to disconnect the clutch-faces b' and b² by 105 the following mechanism:

A link u is pivotally connected at u' to the lower end of the lever t, and at its opposite end said link is pivotally connected at u² to a link u³, said link being pivoted at u⁴ to the top of base a. A lateral movement of the link u³ about its pivot u⁴ toward the left in Fig. 4 will exert a forward pull upon the link 110 u, thus moving the lever t against the tension of spring t⁵ to disconnect the clutch-faces b' and b², and a lateral movement of the link u³ in the opposite direction or toward the right will permit the link t to be drawn back by 115 the spring t⁵, thus moving the pulley b toward the pulley b³ to bring the clutch-faces b' and b² in contact, as will be clear from an inspection of Figs. 2 and 4. The lateral movement of the link u³ is imparted by the shaft w, 120 which shaft is mounted to have a longitudinal sliding movement and a rocking movement in the bearings w', and said shaft w has a fixed grooved collar w², (see dotted lines, Fig. 4,) which collar engages a roller w⁵, mounted upon the pivot u² of the links u and u³. The shaft w is moved longitudinally in one direction by a spring w³, which is coiled 125 upon said shaft, one end of such spring bear-

ing against the bearing w' at the left of the machine, as shown in Fig. 4, and the other end of said spring bearing against the grooved collar w^2 . The shaft w is moved in the opposite direction against the tension of spring w^3 by a lug w^4 , which is fixed to the rear face of the gear b^5 and which is arranged to engage a lug w^5 , carried by a collar w^6 , fixed to the left-hand end of the shaft w . When the lug w^4 engages the lug w^5 and moves the shaft w laterally to the left, as shown in Fig. 4, it causes said shaft, by means of the grooved collar w^2 , to swing the forward end of the link u^3 to the left, thus pulling forward upon the link u , and disconnects the clutch-faces b' and b^2 , thus stopping the rotation of shaft B and the movements of the knife-carriage C, and said parts will remain at rest so long as the lug w^5 is held by the lug w^4 . A rocking of the shaft w in its bearings will move the lug w^5 away from the rear face of the gear b^5 and disengage the same from the lug w^4 , thus permitting the spring w^3 to move the shaft to the right, which swings the end of link u^3 to the right and permits the spring t^5 to draw back the lower end of the lever t and throw the clutch-faces b' and b^2 into contact to start the rotation of the shaft B and the movement of the knife-carriage C. It is designed that as soon as the shaft w has been rocked to remove the lug w^5 from engagement with the lug w^4 and moved to the right by the spring w^3 , as described, to start the shaft B said shaft w will be instantly returned to its former position in order to place the lug w^5 in position to be engaged by the lug w^4 as said lug w^4 comes around to the stopping position to stop the rotation of shaft B.

To secure the above-suggested result and also to provide for a stopping of the reciprocation of the knife-block carriage C independently of the backward rocking of the shaft K and the lowering of the work-support H, the connection between the link p^{10} and the shaft w is a loose connection arranged to be automatically disconnected when the shaft w is moved laterally by the spring w^3 and connected when the shaft w is pulled laterally by the lug w^4 . This connection comprises a collar w^7 , which is loosely mounted upon the shaft w and through which the shaft is free to move. The collar w^7 has a projecting arm w^8 , to the outer end of which the rod p^{10} is pivotally secured, and said collar is arranged to be rocked in one direction by a downward pull on said rod and to be returned by a spring w^9 , which is connected at one end to said collar and at the opposite end to a fixed portion of the frame. Fixed to the outer or right-hand end of the shaft w is a head w^{10} , in which is formed a suitable bearing w^{11} , receiving a stud or pin w^{12} , which is arranged to have a free sliding movement therein and which is normally projected, as shown in Fig. 4 of the drawings, by means of a spring w^{13} , which is located in the bearing w^{11} and which acts upon the inner end of said stud. The

stud w^{12} is arranged to engage an aperture w^{14} , formed in a lug w^{15} , projecting from the collar w^7 , when the shaft w is moved laterally toward the left in Fig. 4, so that the collar w^7 will be locked to the shaft w to rock said shaft when the rod p^{10} is drawn down to remove the lug w^5 from contact with the lug w^4 . A movement of the shaft w to the right under the action of the spring w^3 will remove the stud w^{12} from the aperture w^{14} , thus disconnecting the shaft w from the collar w^7 , when said shaft will immediately be returned to the position shown in Fig. 4 by a spring w^{16} , which at one end is connected to the collar w^2 on said shaft and at its other end to a fixed part of the frame. By the above arrangement the shaft w may be returned to the position shown in Fig. 4 to place its lug w^5 in position to be engaged by the lug w^4 before the rod p^{10} is released by the rocking of the shaft K, so that work-support may be held in its raised position until the knife-block carriage has made a complete reciprocation.

When the shaft w is moved to the left by the lug w^4 engaging the lug w^5 , the inner face of the head w^{10} will be brought close to the outer face of the collar w^7 , the stud w^{12} being forced into its bearing against the tension of the spring w^{13} , and as the collar w^7 is rotated backward by the release of the rod p^{10} as the shaft K is rocked to lower the work-support the stud w^{12} will be forced into the aperture w^{14} as said aperture comes opposite the said stud, whereby the shaft w and the collar w^7 will be locked together and said shaft will be rocked upon a downward pull of the rod p^{10} .

In order to properly position the counter to be skived upon the work-support H, I have provided suitable guides or gages arranged to contact with the edge of the counter and have arranged such guides or gages in such manner that when the work-support H is lowered the guides or gages will project above the upper surface of the work-support and when said work-support is raised said guides or gages will be below the surface of the work-support, so as to be out of the way of the reciprocating skiving-knives. The guides or gages in the machine of the drawings comprise suitable vertically-extending pins or rods x , which rods at their lower ends are adjustably connected to suitable brackets or arms x' , fixed to the base a , said rods x passing through bearings x^2 in the work-support H. The rods x are adjusted to bring their upper ends in such a position that when the work-support H is lowered said rods will project above the surface thereof, as clearly shown in Fig. 1; but when said work-support is raised to bring the counter thereon in position to be acted upon by the skiving-knives the ends of said rods will fall below the surface of the work-support and be out of the way of the reciprocating knives.

In the operation of the machine of the draw-

ings the counter is placed upon the upper surface of the work-support and properly positioned by means of the rods x . The depression of the treadle (not shown) causes the rod p^6 to actuate the bell-crank lever p^4 , causing the fork p' to move the pulley k^2 toward the disk p , thus locking the pulley k^2 to the shaft K and rocking the shaft K to cause the cam h^9 to raise the work-support toward the reciprocating knife-carriage, the vertical movement of the work-support causing the clamp M to clamp the central portion of the counter and hold it fixedly in position on the work-support, as hereinafter described. The rocking of the shaft K has caused the pin p^8 to engage the hooked end of the rod p^{10} , drawing down said rod and through the collar w^7 rocking the shaft w to remove the lug w^5 from contact with the lug w^4 , thus permitting the spring w^3 to move the shaft w to the right and disconnecting said shaft from the collar w^7 and causing the collar w^3 on said shaft to move link u^3 laterally to the right, as shown in Fig. 4, and permitting spring t^5 to rock the lever t to move the pulley b toward the pulley b^3 to bring the clutch-faces b' and b^2 in contact to impart a rotary motion to shaft B . The rotation of shaft B will, by means of the gear b^4 and b^5 , impart a rotation to shaft B' and through the link c reciprocate the knife-block carriage C , as before explained. The knife-block D in Fig. 1 is shown in a horizontal position, being a position of inactivity intermediate between the extreme oscillations of said knife-block D . In Fig. 5, however, the knife-block D is shown in position in which it works on a lateral reciprocation toward the right. In this position the knife d at the right-hand end of the knife-block D as said knife-block is moved toward the right will engage the portions of the counter projecting above the die-plate h and skive off and remove said portions. As the knife-block carriage C reaches the limit of its stroke toward the right the lug or projection d^x on the knife-block D engages the spring-plunger d^5 , and upon its continued movement toward the right moves said plunger, thus compressing its spring, and as the finger e^8 of the bolt E comes in contact with the arm e^9 said bolt will be forced back against the tension of the spring e and its end removed from the notch e^6 , thus permitting the plunger d^5 to oscillate or rock the knife-block D on its pivot, raising the right-hand end of said knife-block and lowering the left-hand end, the bolt on the lowered end locking said knife-block for its return stroke, and as said knife-block returns the knife d on the left-hand end of the knife-block will skive off the projecting portions at the left-hand end of the counter, and as the knife-block carriage C reaches the limit of its stroke to the left the bolt E on the left will be released in a manner before described, permitting the plunger at the left-hand end of the machine to oscillate the knife-block and set it in position (shown in Fig. 5) for another cycle of operation. As soon

as the shaft w was released from the collar w^7 the spring w^{16} returned said shaft to the position shown in Fig. 4, placing the lug w^5 on said shaft in position to be engaged by the lug w^4 on the gear b^5 , and as the lug w^4 engages the lug w^5 the rotation of the gear b^5 will cause the shaft w to be moved laterally to the left against the tension of the spring w^3 , thus moving the link u^3 to the left, and by means of the connecting-rod u draw forward the lower end of the lever t , causing said lever to move back the pulley b along the shaft B , disconnecting the clutch-faces b' and b^2 , and stopping the rotation of shafts B and B' and the reciprocations of the carriage C , whereupon the operator removes his foot from the treadle, thus disconnecting the pulley k^2 from the shaft K and permitting the spring k^5 to rock said shaft backwardly to lower the work-support and also permitting the spring w^3 to turn the collar w^7 in position to bring the aperture w^{14} in line with the stud w^{12} , whereupon the stud w^{12} will engage the aperture w^{14} and lock shaft w to the collar w^7 , to be again actuated, as hereinbefore described.

Having fully described the construction and mode of operation of my invention, I claim as new and desire to protect by Letters Patent of the United States—

1. In a skiving-machine, the combination with a reciprocating carrier and knives thereon arranged for alternate independent operation, of means controlled by the reciprocations of the carrier to alternately move said knives into and out of operative position during each reciprocation of said carrier to skive opposite ends of the material from the medial portion thereof toward each end, substantially as described.

2. In a skiving-machine, the combination with a reciprocating carrier, of an oscillating knife-block mounted thereon, knives mounted on the knife-block at each end thereof, and means to oscillate said knife-block upon the reciprocation of the carrier to alternately place the knives in position to skive opposite ends of the material from the medial portion thereof toward each end, substantially as described.

3. In a skiving-machine, the combination with a reciprocating carrier, of knives thereon arranged for independent operation to skive opposite ends of the material from the medial portion thereof toward each end, means controlled by the reciprocations of said carrier to alternately move one knife into operative position and to move the other knife out of operative position, and locking devices to lock said knives in and out of operative position, substantially as described.

4. In a skiving-machine, the combination with a reciprocating carrier, of an oscillating knife-block mounted thereon carrying a knife at each end thereof, means controlled by the reciprocations of said carrier to oscillate said knife-block to alternately place the knives in position to skive opposite ends of the mate-

rial from the medial portion thereof toward each end, and locking devices arranged to hold said knife-block in its different positions, substantially as described.

5 5. In a skiving-machine, the combination with a reciprocating carrier, of an oscillating knife-block mounted thereon, knives at opposite ends of said knife-block, means to oscillate said knife-block to raise one knife and lower the other as said carrier is reciprocated to place said knives alternately in position to skive opposite ends of the material from the medial portion thereof toward each end, and locking devices also controlled by the reciprocations of said carrier to release the knife-block as the carrier reaches the end of its stroke in either direction to permit the oscillation of said knife-block, substantially as described.

10 6. In a skiving-machine, the combination with a horizontally-reciprocating carrier, carrying a suitable skiving-knife, of a work-support arranged to support the material to be skived, means to impart relative movements to the carrier and work-support to place the work in position to be acted upon by the knife, and means controlled by such relative movements of the knife-carrier and work-support to impart relative reciprocations to the carrier and work-support to cause the knife to operate upon the material, substantially as described.

15 7. In a skiving-machine, the combination with a reciprocating carrier, of an oscillating knife-block mounted thereon, and knives mounted on said knife-block for independent alternate action, means to oscillate said knife-block to raise one end and lower the other as said carrier is reciprocated to alternately place said knives into position to skive opposite ends of the material from the medial portion toward each end, said means being normally inactive and brought into action by the movement of the carrier, substantially as described.

20 8. In a skiving-machine, the combination with a movable work-support, of a yoke-shape work-clamp arranged to engage and clamp the medial portion of the material upon the upward movement of the work-support, and

to release said material upon the downward movement of the work-support, substantially as described.

9. In a skiving-machine, the combination with a reciprocating carrier carrying a skiving-knife, of a work-support movable toward and from the plane of reciprocation of the carrier, and connected mechanisms timed and arranged to cause a reciprocation of the carrier after the work-support has brought the work into position to be acted upon by the knife, and to lower the work-support after such reciprocation of the carrier, substantially as described.

10. In a skiving-machine, the combination with a reciprocating knife-carrier, of a work-support movable toward and from the knife-carrier, a cam-shaft to raise the work-support, a shaft and connecting devices to actuate the knife-carrier and suitable clutches and controlling devices to cause the knife-carrier-actuating shaft to be set in rotation by the rocking of the cam-shaft to raise the work-support, substantially as described.

11. In a counter-skiving machine, the combination with a work-support, of skiving-knives arranged to skive a counter placed on said work-support, and means to actuate said skiving-knives to cause said knives to alternately make skiving cuts from the medial portion of the counter toward each end thereof, substantially as described.

12. In a skiving-machine, the combination with a work-support, of a skiving-knife, means to move the work-support toward and from the skiving-knife and a suitable work-gage mounted on a fixed support and arranged to position the work upon the work-support, said gage arranged to be projected above the face of the work-support as said work-support moves away from the skiving-knife, and to be retracted below the work-support as said work-support moves toward the skiving-knife, substantially as described.

In testimony whereof I affix my signature in presence of two witnesses.

WILLIAM J. YOUNG.
